Russell Wheeler and Stephen A. Bailey of Utica, N.Y.

Letters Patent No. 2005 Dated December 6, 1864.

Design for a Cook's Stove.

The schedule referred to in these Letters Patent and making part of the same, shall whom it may concern,

Be it known that we, Russell Wheeler and Stephen A. Bailey, of the City of Utica, in the County of Oneida and State of New York, have invented a new and improved design for a cook's stove and we hereby declare that the following is a full and exact description thereof, reference being had to the accompanying drawings: The nature of our invention consists in a new design for a cook's stove.

To enable others skilled in the art to make and use our invention we will proceed to describe its design and construction.

Fig. 1. designates the stove when it is set up. A A in figures 1 and 2. designate the moulding on the edge of the upper or top plate. B B in figures 1 and 2. designate the front doors with ornament in the upper part and ornament in the centre of the lower part. C C in figures 1 and 2. designate the oven doors with ornament in the centre of each. D D in figures 1 and 2. designate the moulding on the lower or bottom plate. The stove is of cast iron and is represented by the above figures and letters on the accompanying drawings.

What we claim as our invention and design, and
desire to secure by letters Patent are the form, ornaments, and
design of a cook stove as a base represented and described.
